UNITED STATES PATENT OFFICE

2,079,726

GARMENT STRETCHER

Frank L. Wilson, Raymondville, Tex.

Application May 28, 1936, Serial No. 82,360

1 Claim. (Cl. 223—70)

The present invention pertains to new and useful improvements in garment stretchers and has for one of its important objects to provide, in a manner as hereinafter set forth, a machine of this character embodying a novel construction, combination and arrangement whereby the garment may be subjected to the action of steam to facilitate the stretching thereof, the invention further including steam heating means for drying the garment after said garment has been stretched.

Another very important object of the invention is to provide a machine of the aforementioned character embodying novel means through the medium of which a garment may be expeditiously and accurately stretched to the desired size.

Still another very important object of the invention is to provide a machine of the character described comprising a plurality of stretching bars, together with novel means for actuating said stretching bars.

Still another very important object of the invention is to provide a garment stretcher including a slidably and yieldingly mounted movable hanger for supporting the garments on the stretching bars.

Other objects of the invention are to provide a garment stretcher of the character set forth which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a garment stretcher constructed in accordance with the present invention.

Figure 2 is a view in front elevation thereof.

Figure 3 is a view in vertical section through the housing on the upper portion of the machine showing, in side elevation, the lazy tongs operating mechanism.

Figure 4 is a top plan view of the lower portion of the machine.

Figure 5 is a vertical sectional view through the lower portion of the machine.

Figure 6 is a detail view in elevation of the lazy tongs guide rod.

Figure 7 is a view in horizontal section, taken substantially on the line 7—7 of Figure 3.

Figure 8 is a detail view in top plan, showing the means for supporting the clamping bars or jaws for substantially universal swinging movement, the cap being removed.

Figure 9 is a view in vertical section through

an intermediate portion of one of the stretching bars.

Figure 10 is a vertical sectional view through an intermediate portion of one of the stretching bars, taken at right angles to Figure 9.

Referring now to the drawings in detail, it will be seen that the embodiment of the invention which has been illustrated comprises an annular base 1 from which a supporting frame 2 rises. Mounted on the supporting frame 2 and spaced above the base 1 is an annular casing 3. The front portion of the casing 3 is split, as at 4, and mounted in said split 4 is a vertical bar 5. Pivotally mounted on the supporting frame 2 are foot levers 6 and 7 which are operable in the split 4 on opposite sides of the bar 5. Vertically elongated plates 8 are mounted on the casing 3 adjacent the split 4, said plates being graduated and having notches 9 on their inner edges engageable by the foot levers 6 and 7 for releasably securing said foot levers in adjusted position. Mounted in the casing 3 is an annular perforated steam spray 10 which is connected with a steam supply pipe 11, said spray 10 being controlled by a suitable valve 12. Also mounted in the casing 3 and connected to the supply pipe 11 is a heating drum 13 which is provided with a drain valve 14.

In the upper portion of the frame 2 are radial arms 15 on the inner ends of which a vertical sleeve 16 is mounted. Adjustably mounted in the sleeve 16 is a tubular post which is designated generally by the reference numeral 17. The post 17 is secured in adjusted position by a set screw 18. The post 17 comprises a plurality of sections which are connected by couplings 19 to 24, inclusive. Mounted on the lower section of the tubular post 17, above the sleeve 16, is a sleeve 25, said sleeve being vertically adjustable and secured in adjusted position by an elongated set screw 26. Radiating from the sleeve 25 are arms 27 on the outer ends of which a covered substantially oval frame 28 is mounted. Projecting from one end of the frame 28 is a bracket 29 on which a multiple socket 30 is hingedly mounted, as at 31. Mounted for swinging movement on the member 30 are clamping arms 32 which are also covered and which are adapted to coact with the substantially oval frame 28 for securing the lower end portion of the garment. The pivoted end portions of the clamps 32 include headed shanks 33 (see Figure 8) mounted in the multiple socket member 30. A stop 34 is provided on the bracket 29 for limiting the swinging movement on the multiple socket member 30 toward the frame 28. A coil spring 35 permanently connects the pivoted end portions of the clamps 32. The free end portions of the clamps 32 are detachably connected by a coil spring 36 which is engageable with a hook 37. Also mounted on the

sleeve 25 is a substantially U-shaped guide 38 provided with a set screw 39 the purpose of which will be presently set forth.

Collars 40 and 41 are slidably mounted on the 5 tubular post 17 above and below the coupling 23. Pivotedly mounted on the collars 40 and 41 are lazy tongs 42. Also slidably mounted on the post 17, above and below the coupling 20, are collars 43 and 44 having mounted thereon lazy tongs 45. 10 Coil springs 46 are mounted on the post 17 and engaged with the slidable collars 40, 41, 43 and 44 for yieldingly urging the lazy tongs 42 and 45 toward retracted position. Pulleys 46 are connected to the slidable collars 40 and 41 and 15 trained around said pulleys are chains 47 and 48. One end of the chains 47 and 48 is connected to the coupling 23. The other end of the chain 48 is connected to the chain 47 at an intermediate point and the other end of said chain 47 is 20 adjustably connected to the foot lever 6 through the medium of a hook 49. Pulleys 50 are mounted on the slidable collars 43 and 44 and trained thereon are chains 51 and 52 which are connected, at one end, to the coupling 20. The other 25 end of the chain 52 is connected to the chain 51 at an intermediate point and the other end of said chain 51 is adjustably connected to the foot lever 7 by a hook 53. Side stretching bars 54 are mounted on the free ends of the lazy tongs 42 and 45, links 55 being interposed between said stretching bars and the lower lazy tongs 45.

As best seen in Figures 3 and 7 of the drawings, rods 56 project horizontally from the couplings 20 and 23 and mounted on the outer end portions 30 of said rods is a substantially cylindrical housing 57. The housing 57 is open at its lower end and closed at its upper end, as at 58. It will be noted that the housing 57 encloses the lazy tongs operating mechanism, such as the slides 40, 41, 43 35 and 44, the coil springs 46, etc. Further, the housing 57 is provided with vertical slots 59 in which the lazy tongs 42 and 45 are operable. Extending between the rods 56 on one side of the post 17 is a guide rod 60 which is engaged 40 between pairs of ears 61 which project from the slidable collars 41 and 43. The reference numeral 62 designates a removable garment hanger which is slidably mounted on the upper end portion 45 of the post 17 above the housing 57. A coil spring 63 yieldingly supports the hanger 62, said coil spring resting on the coupling 24.

The rods 56 project through the housing 57 and mounted on the outer ends thereof are brackets 64 on which front and back bars 65 50 and 66, respectively, are mounted. The brackets 64 include hinges 67 to permit swinging movement of the bars 65 and 66. It may be well to here state that the bars 54, 65 and 66 are of suitable resilient material. Further, these bars comprise upper and lower metallic strips 68 and 69, 55 respectively, which are riveted together and which are enclosed in a covering 70 of suitable material. The reference numeral 72 designates a chain having its upper end connected to the 60 post 17 by a hook 73. The lower end of the chain 72 is adapted to be adjustably secured in the guide 38 on the sleeve 25 by the set screw 39.

Briefly, the operation of the machine is substantially as follows:

With the side bars 54 in retracted position, the hanger 62 is inserted in the garment to be stretched and said hanger is then mounted on the upper end of the post 17. Of course, the bars 54, 65, and 66 are engaged in the garment. With

the frame 28 secured in the desired position on the post 17, the lower portion of the garment is secured to said frame by the clamps 32. The valve 12 may then be opened for the purpose of discharging steam upwardly from the annular 5 spray head 10 into the garment. The reference numeral 74 designates a flexible conduit for the steam having its upper end secured to the frame 28 and its lower end secured to the casing 3. To move the side stretching bars 54 outwardly the 10 foot levers 6 and 7 are swung downwardly and by observing the graduations on the plates 8 the garment may be conveniently and accurately stretched to the desired size. Attention is here invited to the fact that the construction and arrangement is such that the upper and lower lazy tongs 42 and 45 may be independently actuated. Further, the stretching bars 54, 65 and 66 are possessed of different degrees of resilience at different points to conform in a general way to the 15 shape of the garment. For example, the lower steel strips 69 are comparatively stiff to expand the lower portion of the garment below the hips to its fullest extent. After the stretching operation has been completed the valve 12 is closed to 20 shut off the steam from the spray head 10 but the garment is permitted to remain on the machine for a length of time sufficient to be dried by heat from the steam drum or cylinder 13. By means of the valve 14 condensation may be conveniently 25 drained from the drum or cylinder 13. After being thus dried the garment may be removed from the machine by releasing the clamps 32, retracting the bars 54 and then lifting the hanger 62 off the post 17.

It is believed that the many advantages of a garment stretcher constructed in accordance with the present invention will be readily understood, and although a preferred embodiment of the machine is as illustrated and described, it is to be 40 understood that changes in the details of construction and in the combination and arrangement of parts may be resorted to which will fall within the scope of the invention as claimed.

What is claimed is:—

A garment stretcher of the class described, comprising, in combination, a base, a supporting structure mounted on said base, a casing mounted on said supporting structure, a pair of foot levers pivotally mounted on the supporting structure, the casing having a vertical opening therein accommodating the foot levers, means on the casing engageable by the foot levers for releasably securing said foot levers in adjusted position, a vertical post mounted on the supporting structure, a horizontal frame adjustably mounted on the post, a flexible conduit extending between said frame and the casing, lazy tongs mounted on the post, means operatively connecting certain of the lazy tongs to one of the levers 45 for actuation thereby, means operatively connecting the other of said lazy tongs to the other lever for actuation thereby, bars for stretching a garment mounted on the lazy tongs, clamps for detachably securing the lower portion of the 50 garment to the frame, means in the casing for discharging steam upwardly through the flexible conduit into the garment, a steam drum mounted in the casing for heating and drying the garment, and a slidable hanger for the garment 55 yieldingly mounted on the upper end portion of the post.

FRANK L. WILSON.
